UNITED STATES PATENT OFFICE.

WILLIAM T. BATE, OF CONSHOHOCKEN, PENNSYLVANIA.

APPARATUS FOR THE MANUFACTURE OF GAS.

SPECIFICATION forming part of Letters Patent No. 431,932, dated July 8, 1890.

Application filed August 16, 1886. Serial No. 211,031. (No model.) Patented in England December 11, 1888, No. 18,127.

To all whom it may concern:

Be it known that I, WILLIAM T. BATE, a citizen of the United States, residing at Conshohocken, Montgomery county, Pennsylvania, have invented certain Improvements in Apparatus for the Manufacture of Gas, (for which I have obtained Letters Patent in Great Britain, No. 18,127, dated December 11, 1888,) of which the following is a specification.

10 My invention relates to that class of gas apparatus in which the gas is produced by decomposing steam, mixing hydrocarbon vapor therewith, and fixing the gas by effecting the intimate commingling of the decomposed 15 steam and oil vapor under intense heat, my invention comprising certain improvements in the details of construction of gas apparatus of this character.

One of the objects of my invention is to so 20 construct the top of the metal casing that the application of the fire-brick lining can be readily effected and the joints protected, further objects being to provide for the ready removal 25 of the tar from the wash-box, and to prevent the unsealing of the gas-pipes which terminate in said box.

In the accompanying drawings, Figure 1 is a side view of a gas apparatus constructed in accordance with my invention; Fig. 2, a plan 30 view of part of the same, partly in section; Fig. 3, a longitudinal section, partly in elevation, of part of the apparatus on a larger scale than Fig. 1; Fig. 4, a transverse section, partly 35 in elevation, on the line 1 2, Fig. 3; Fig. 5, a section, partly in elevation, on the line 3 4, Fig. 4; and Fig. 6 a perspective view of one of the blast-pipes shown in Fig. 4.

A represents the fire-box or furnace, and B the superheater or fixing-chamber of gas apparatus, such as that to which my invention 40 relates, the superheater having a dome D, which is provided with a valved elbow-pipe a, communicating with a hydraulic main or wash-box F, the discharge end or mouth of 45 said elbow-pipe a being submerged in the water in said box. Usually two sets of such apparatus are placed side by side, the elbow-pipes of both sets communicating with the wash-box, and the sets being worked alternately—that is to say, gas being made in one 50 set while the products of combustion are being allowed to pass through the superheater

of the other set, and to escape from the dome of the same into the smoke-stack, the valve in the elbow-pipe of the latter set being closed, 55 and the valve b on the top of the dome being open, while in the set in which gas is being made the valve in the elbow-pipe is open and the valve at the top of the dome is closed. The fire-place and superheaters in such apparatus usually consist of an outer rectangular casing G of wrought-iron plates with a suitable fire-brick lining f.

In order to relieve the wrought-iron casings of each chamber from the strain due to the 60 expansion of the fire-brick lining, I interpose between said casing and the lining a filling g, preferably of loam, asbestos, or some other material which, while possessing a considerable degree of elasticity, will not be injuriously affected by the heat, this filling being compressed as the fire-brick lining expands, so that the outer metal casing of the chamber is not unduly strained by such expansion. The internal T-iron braces for the 65 iron casing are placed vertically, as shown in Fig. 2, so as to permit the close packing of the filling between the fire-brick lining and the casing and around said braces, the inwardly-projecting vertical ribs formed by the 70 T-irons offering no obstacle to such packing, and being, therefore, preferable to horizontal or transverse braces. The casing of the superheater B is at some distance from that of the fire-place A, the two casings being connected 75 by a neck h, so that while there is free communication from one chamber to the other, an air-space intervenes between the casings of the two chambers, and a similar air-space is formed between the chambers of one set 80 of apparatus and those forming the adjoining set, whereby a free circulation of air on all four sides of each chamber is provided, the heat transmitted to the metal casings of the chambers being rapidly radiated therefrom, and the said casings prevented from 85 becoming so highly heated as to cause the plates of which they are composed to warp or buckle, and thus strain or disrupt the joints between the plates. I do not, however, claim 90 as my invention the separation of the various structures of gas apparatus, as this has heretofore been proposed.

It is usual to complete the wrought-iron

casing of each chamber before the application of the fire-brick lining thereto, the top plate of each chamber having therein a central opening of a size sufficient to permit the introduction of the fuel or to permit the escape of the products of combustion. With an opening of such contracted area in the top plate, however, much difficulty is experienced in laying the bricks to form the lining of the chamber, owing 10 to the fact that when the lining approaches the top of the chamber the bricks must be pushed into place laterally instead of being built up directly from above, as in laying the lower courses. This results in defective lining of 15 the chamber and causes the rapid burning out of said lining and of the wrought-iron casing. I therefore discard the usual plan of riveting the top plate directly to the angle-iron, which extends around the sides of the 20 casing at the top, and secure thereto instead a flanged collar H, the area of the opening of which is almost as great as that of the casing of the chamber. This collar therefore does not materially interfere with the proper laying 25 of the upper courses of fire-bricks, of which the lining of the chamber is composed, and after these courses have been laid up to the level of the top of the collar the top plate H' is applied thereto and secured in position 30 by means of bolts passing through the external flange at the top of the collar through openings around the edges of the plate and through openings in a re-enforcing ring on the top of the plate. These fastening devices are therefore on the outside of the casing, where they are not subjected to heat, and are readily accessible whenever it becomes necessary to remove the top plate H' of the 35 casing for any purpose. The top plate has a central dome I, which, in the case of the firebox, is provided with a detachable cover I', and in the case of the superheater is extended vertically, so as to receive the gas-discharge 40 elbow-pipe a, and so as to provide at its upper end a seat for the valve b.

The smoke-stack J is hung to the roof of the structure, as shown in Fig. 1, or in any other convenient manner, the lower end or mouth of the stack being of considerably 45 greater area than the upper end or mouth of the dome, and being, preferably, some distance above the same, so that air circulates freely around the valve b at all times, and thus prevents such an excessive heating of 50 said valve as would have an injurious effect upon the same; the valve, moreover, being at all times readily accessible for inspection or 55 repairs.

The structure in which the apparatus is located is preferably provided with transverse beams K, which serve as trucks for wheeled hangers K', the latter providing supports for tackle when it is desired to lift the dome or top plate from any of the chambers.

The hydraulic main or wash-box F is mounted upon platforms M, supported upon suitable columns M' at the end of the appa-

ratus, and from the bottom of the box extends a straight discharge-pipe N for the escape of the tar which accumulates in the wash-box, thus 70 very materially reducing the risk of clogging as compared with a wash-box having a discharge-pipe curved or bent, as it must be when the wash-box is located on top of the gas-generating structure. 75

In order to clean the tar from the bottom of the wash-box and direct it to the discharge-pipe N when the valve m, closing the mouth of the same, has been raised, I provide each end of the wash-box with a blast-pipe n, that 80 portion which is within the box being spread and flattened, as shown in Fig. 6, these blast-pipes being in connection with any available source of steam-supply, so that the steam issues therefrom in a broad flat sheet close 85 to the bottom of the box, the tar which may have accumulated in the box being softened under the influence of the heat, and carried forward by the action of the jet until it escapes through the discharge-pipe N. 90

In the operation of duplex gas apparatus of the character which I have described and in which both gas-pipes communicate with the wash-box—one near each end—a violent surging of the water from end to end of the 95 wash-box frequently takes place when the flow of gas through one pipe is cut off simultaneously with the inflow of gas through the opposite pipe, this movement of the water being frequently such as to unseal the mouth 100 of the gas-inlet pipe and permit the hot gas therefrom to enter the wash-box without passing through the water, and explosions sometimes occur from this cause. In order to overcome this difficulty I provide the wash-box at or about the center with a transverse partition P, which terminates some distance from the bottom of the box, so that while it does not cut off communication between the opposite ends of the box it provides an opening of contracted area, through which the 105 water must pass in flowing from one end of the box to the other, thereby preventing any such rapid movement of the water in either direction as would permit a reduction of the 110 level in either end of the box sufficient to unseal the mouth of the pipe communicating therewith. This partition-plate also serves as a means of supporting a guide p for the rod of the valve m. 115

Man-holes, provided with suitable covers s, are formed in the opposite ends and in the front of the wash-box, so that ready access to the interior of the same can be had when necessary. 120

I do not claim, broadly, the use of a steam-jet for the purpose of facilitating the discharge of the contents of a vessel having an inclined bottom, as such a device has been resorted to in many cases. 125

The novel feature of this part of my invention consists in providing the wash-box with a steam-pipe so formed as to discharge a broad flat sheet or sheets of steam close to the 130

inclined bottom of the box and thereby thoroughly clear the same of tar.

Independently-supported wash-boxes have also been proposed; but I am not aware that such a box has been combined with a straight tar-discharging pipe leading vertically downward from the bottom of the same, for the purpose of insuring the free and unobstructed discharge of the tar; and hence my claim on rc this feature of the invention is limited to the specific combination mentioned.

A hydraulic main has been provided with a sealing-box partitioned so as to form a chamber for each dip-pipe; but this box was only 15 intended for occasional use, the dip-pipes being under ordinary circumstances unsealed. The partition in my wash-box, on the contrary, is part of the permanent structure, and its very purpose is to prevent the unsealing 20 of either of the dip-pipes. The partitions in the sealing-box above referred to, moreover, extended to the bottom of the box; and hence divided the same into a number of non-communicating chambers, whereas the partition 25 in my wash-box is discontinued some distance from the bottom of the box, so as not to interfere with the proper flow of water from one end of the box to the other.

A hydraulic main has also been provided 30 with a longitudinal partition parallel with the pipes, and discontinued some distance from the bottom of the box; but it will be evident that such a longitudinal partition is not capable of attaining the object of my transverse 35 partition between the dip-pipes, as it is incapable of preventing rapid flow of water from one end of the box to the other.

I therefore claim as my invention—

1. The combination, in a gas-generating 40 structure, of the fire-brick lining, the side

plates of the metal casing, a top plate, and a collar having upper and lower flanges, the lower flange being secured by an angle-bar to the upper portions of the side plates and the upper flange being bolted to the top plate 45 so that the latter can be readily applied or removed after the building up of the brick-work lining of the casing, substantially as specified.

2. The combination of the wash-box having 50 an inclined bottom with outlet at the lowest point, and a blast-pipe having its discharge-mouth flattened and widened, as set forth, whereby a broad flat sheet of steam directed toward the outlet is discharged close 55 to the bottom of the wash-box, all substantially as specified.

3. The combination of the fixed wash-box having dip-pipes communicating with the same near each end and extending at all times 60 below the normal level of the sealing-liquid in the box, with a transverse shield, whereby the rapid passage of water from one end of the box to the other is obstructed and the unsealing of either dip-pipe thereby prevented, 65 all substantially as specified.

4. The combination of the wash-box having a supply of sealing-liquid, with opposite dip-pipes, and the interposed transverse obstructing-shield discontinued some distance from 70 the bottom of the wash-box, all substantially as specified.

In testimony whereof I have signed my name to this specification in the presence of two subscribing witnesses.

WILLIAM T. BATE.
